His Attorney.

UNITED STATES PATENT OFFICE

148,858

DESIGN FOR A SECTIONAL DISPLAY TABLE

Neel S. Irwin, Weaverville, N. C.

Application July 26, 1946, Serial No. 131,982

Term of patent 14 years

(Cl. D80—9)

To all whom it may concern:

Be it known that I, Neel S. Irwin, a citizen of the United States and a resident of Weaverville, in the county of Buncombe and State of North Carolina, have invented a new, original, and ornamental Design for Sectional Display Tables, of which the following is a specification, reference being had to the accompanying drawing, forming a part thereof.

The figure is a perspective view of a sectional display table, showing my new design.

I claim:

The ornamental design for a sectional display table, as shown.

NEEL S. IRWIN.
